(57)

CLAIM

The ornamental design for a mobile device accessory, substantially as shown and described.

DESCRIPTION

FIG. 1 is a top, right-side, and front perspective view of a mobile device accessory showing my new design;

FIG. 2 is a top plan view thereof;

FIG. 3 is a top, right-side, and rear perspective view thereof; FIG. 4 is a top, right-side, and front perspective view thereof;

FIG. 5 is a top, left-side, and rear perspective view thereof;

FIG. 6 is a top, left-side, and front perspective view thereof;

FIG. 7 is a bottom plan view thereof;

FIG. 8 is a bottom, left-side, and rear perspective view thereof;

FIG. 9 is a bottom, left-side, and front perspective view thereof;

FIG. 10 is a bottom, right-side, and rear perspective view thereof;

FIG. 11 is a bottom, right-side, and front perspective view thereof;

FIG. 12 is a front elevational view thereof shown on an enlarged scale for clarity of disclosure;

FIG. 13 is a rear elevational view thereof shown on an enlarged scale for clarity of disclosure;

FIG. 14 is left-side view thereof; and,

FIG. 15 is a right-side view thereof.

The broken lines in the drawing figures form no part of the claimed design, and they illustrate portions of the mobile device accessory that form no part of the claimed design.

1 Claim, 12 Drawing Sheets
